UNITED STATES PATENT OFFICE.

JOSEPH HANSON AND LESLIE M. FOOTE, OF INWOOD, IOWA.

DEVICE FOR TIGHTENING SILO-HOOPS.

1,075,564.

Specification of Letters Patent.

Patented Oct. 14, 1913.

Application filed August 24, 1912. Serial No. 716,936.

To all whom it may concern:

Be it known that we, JOSEPH HANSON and LESLIE M. FOOTE, citizens of the United States, residing at Inwood, in the county of Lyon, State of Iowa, have invented a new and useful Device for Tightening Silo-Hoops, of which the following is a specification.

The device forming the subject matter of this application is adapted to be employed for tightening the hoops which surround a silo or like structure.

Hitherto it has been necessary to ascend the silo, in order that the higher hoops thereof may be tightened, and in the tightening of the hoops, wrenches and like tools hitherto have been necessary. In the present invention, the hoops may be tightened while the operator is standing upon the ground, it being unnecessary to climb the silo, or to employ tools of any sort for effecting the tightening operation.

The invention aims to provide novel means for connecting the ends of the hoop, to provide novel means for producing relative movement between the ends of the hoop, whereby the hoop may be tightened, and to provide means whereby the hoop of a silo or like structure may be tightened while the operator is standing upon the ground.

The invention aims further, to improve generally, tightening devices of the sort hereinafter set forth.

With the above and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the accompanying drawings:—Figure 1 shows the invention in perspective, applied to a silo. Fig. 2 is a front elevation of the invention, parts being broken away and sectioned. Fig. 3 is a side elevation of the invention, a portion of the silo appearing in section. Fig. 4 is a section of the casing which receives the ends of the hoop, the cutting plan being passed along the line 4—4 of Fig. 2. Fig. 5 is a section of the casing along the line 5—5 of Fig. 2.

Referring to the drawings, the numeral 1

indicates generally a silo, comprising, as usual, a plurality of staves 2. The silo 1 is surrounded by a plurality of hoops, one of which is shown in the drawing, and denoted generally by the numeral 3, the ends 60 of the hoop 3 being indicated by the numerals 4 and 5.

The ends 4 and 5 of the hoop 3 pass through a casing which is denoted generally by the numeral 6. The casing 6 fits 65 against the silo 1 and comprises a pair of integrally formed, frusto-conical parts 7 and 8, the smaller ends of which are oppositely disposed. In the part 7 there is an opening 9 through which the ends 5 of the hoop 3 70 passes, and in the part 8 there is an opening 10 through which the part 4 of the hoop 3 is extended. The openings 9 and 10 are disposed in intersecting relation, the openings being tangentially disposed with respect to 75 the periphery of the silo 1, so that the ends 4 and 5 of the hoop 3 may stand away from the outer face of the silo slightly. The position of the ends of the hoop, and notably the end 5, is of importance since thereby, 80 the use of the tightening device hereinafter described is permitted. Ordinarily the ends 4 and 5 of the hoop 3 are threaded, and upon the end 4 may be mounted a nut 11, which, engaging the portion 8 of the casing 6 serves 85 to hold the end 4 in place when tension is placed upon the hoop 3 in a manner hereinafter described.

Threaded upon the end 5 of the hoop 3 is a ratchet nut 12, having lateral extensions 14 and 15, the extension 15 abutting against a washer 16, the washer 16 surrounding the end 5 and abutting against one end of the casing 6.

The invention further includes a lever 95 which is denoted generally by the numeral 17, the lever 17, having bifurcations 18 which are journaled for rotation upon the extensions 14 and 15. Supported in the bifurcations 18 is a shaft 19 which supports pivotally a pawl 20, the pawl 20 being adapted to engage with the ratchet nut 12. A spring 21 is shown, the same, in its intermediate portion, being coiled about the extension 15 of the ratchet nut 12, the spring 100 having at its lower end a hook 22 which engages with the end 5 of the hoop 3 between the washer 16 and one side face of the ratchet nut 12. At its opposite end, the spring 21 is equipped with a hook 23 which 105

engages one edge of the lever 17. In order to provide for the operation of the lever 17, the same is equipped at one end with a depending actuating member 24 which may be a cord or rod, the same being of sufficient length to extend to a point well within the reach of a person standing upon the ground. The actuating member 24 may be provided at its lower end with a handle 25.

10 In practical operation, a person standing upon the ground, seizes the actuating member 24 and pulls downwardly upon the same, motion being thereby imparted to the lever 17, the lever 17 swinging with the extensions 15 14 and 15 as a fulcrum. When the lever is swung, the pawl 20 will engage the ratchet nut 12, imparting a rotation to the ratchet nut 12, and since the ratchet nut is threaded upon the end 5 of the hoop 3, the ratchet 20 nut will travel along end 5 of the hoop and abut against the washer 16, the same abutting against the casing 6, the hoop 3 being thereby put under tension. When the actuating member 24 is released, the lever 17 25 at its free end will be swung upwardly due to the action of the spring 21, which, during

the depression of the free end of the lever 17 has been put under tension.

Having thus described the invention, what is claimed is:—

30 In a device of the class described, a hoop; a casing in which the ends of the hoop are received; means for securing one end of the hoop in the casing; a ratchet nut threaded on the other end of the hoop and bearing 35 against the casing; a lever fulcrumed on the ratchet nut; a pawl on the lever and co-operating with the ratchet nut; and a spring engaged in its intermediate portion with the nut, one end of the spring being connected with the lever and the other end of the spring being connected with the first specified end of the hoop for sliding movement longitudinally of said end.

40 In testimony that we claim the foregoing 45 as our own, we have hereto affixed our signatures in the presence of two witnesses.

JOSEPH HANSON.
LESLIE M. FOOTE.
